US00D751579S

(12) **United States Design Patent**
Hansing et al.

(10) **Patent No.:** US D751,579 S
(45) **Date of Patent:** ** Mar. 15, 2016

(54) **DISPLAY SCREEN WITH GRAPHICAL USER INTERFACE**

(71) Applicant: **Microsoft Corporation**, Redmond, WA (US)

(72) Inventors: **Britt Hillary Hansing**, Seattle, WA (US); **Christina Francis Colcernian**, Seattle, WA (US)

(73) Assignee: **Microsoft Corporation**, Redmond, WA (US)

(**) Term: **14 Years**

(21) Appl. No.: **29/490,032**

(22) Filed: **May 6, 2014**

(51) LOC (10) Cl. **14-04**

(52) U.S. Cl.

USPC **D14/485**

(58) **Field of Classification Search**

USPC D14/485-488, 489-495; D20/11, 22, D20/27

CPC G06T 2200/24; G06F 3/0489; G06F 15/0225; G06F 17/30115; H04N 21/482;

H04N 5/44543; H04N 21/478; H04H 60/72

(57) **CLAIM**

The ornamental design for a display screen with graphical user interface, as shown and described.

DESCRIPTION

The FIGURE is a front view of a display screen with graphical user interface showing our new design.

The broken line showing of the rectangles, the magnifying glass, the remainder of the user interface, and the remainder of the display screen is for environmental purposes only and forms no part of the claimed design.

1 Claim, 1 Drawing Sheet
